DESIGN FOR A TABLE FOR AN IRONING MACHINE OR THE LIKE

John G. Rideout, Toledo, Ohio, assignor to The
Maytag Company, Newton, Iowa, a corporation
of Delaware

Application October 3, 1935, Serial No. 58,826

Term of patent 14 years

To all whom it may concern:

Be it known that I, John G. Rideout, residing at Toledo, in the county of Lucas and State of Ohio, a citizen of the United States, have invented a new, original, and ornamental Design for a Table for an Ironing Machine or the like, of which the following is a specification, reference being had to the accompanying drawing, forming a part thereof.

Fig. 1 is a perspective view of a table for iron-

ing machine or the like showing my new design with the end extensions in lowered position.

Fig. 2 is a perspective view at a slightly different angle from that of Fig. 1 and showing the end extensions in elevated position.

I claim:

The ornamental design for a table for an ironing machine or the like substantially as shown.

JOHN G. RIDEOUT.
